UNITED STATES PATENT OFFICE

100,010

DESIGN FOR A JAR

Davis Factor, Los Angeles, Calif., assignor to Max Factor & Co., Los Angeles, Calif., a corporation of Delaware

Application April 8, 1935, Serial No. 56,264

Term of patent 14 years

To all whom it may concern:

Be it known that I, Davis Factor, a citizen of the United States, residing in the city and county of Los Angeles, State of California, have invented a new, original, and ornamental Design for a Jar, of which the following is a specification, reference being had to the annexed drawing forming a part thereof.

The accompanying drawing includes two views of a jar embodying my new design.

Fig. 1 is a plan looking down on the cover of the jar; and

Fig. 2 is an elevational view.

I claim:

The ornamental design for a jar, as shown.

DAVIS FACTOR.
